TENSION DEVICE

James Watt Ijsbrand Heijnis, Arnhem, Netherlands, assignor to American Enka Corporation, Enka, N. C., a corporation of Delaware

Application October 10, 1950, Serial No. 189,397
In the Netherlands October 17, 1949

4 Claims. (Cl. 242—149)

1

This invention relates to a device for use in the winding of threads, and more particularly to a device for imparting a constant additive tension to a thread as it is being wound.

In the many various thread handling operations in the textile industry, control of the tension of the thread being handled is generally of considerable importance. To afford tension control for such operations there have been many types of tensioning devices, or thread brakes which are well known in the art. In general, there are two main types—the "finger" device and the "pinch" device.

In the "finger" tensioning device, the thread is conducted over a series of curved surfaces which exert a snubbing action on the thread in accordance with the total angular contact and the coefficient of friction between thread and surface. When the yarn is taken up by a machine at a constant speed from a source that does not produce variations in feed tension, or pretension, such a finger tensioning device functions satisfactorily. In other thread handling operations, however, the yarn is not supplied at an even tension, and in such cases the use of finger tensioning is undesirable, for the variation of tension of the incoming thread is multiplied to give an even greater output tension variation, which often may produce defects such as "shiners" in a fabric woven from the particular package of thread in which the tension variations occurred.

To overcome this multiplication of tension, the "pinch" tension device was designed to impart a fixed additive tension to the thread irrespective of the tension of the thread as it approaches the device. In this device, the thread is drawn between two surfaces which are forced together by means such as a spring or weight.

In still other thread handling operations, the thread is not taken up at a constant speed but is collected either at a gradually changing speed, as in the winding of a cone or tube at constant spindle speed, or at a varying speed, as in the winding of a seriplane board. Both finger and pinch tension devices produce higher tensions at such higher thread speeds.

There are several further problems in the winding of threads with a pinch tension device. When a twisted yarn is passed through such a device, the pressure exerted on the thread by the device tends to cause "run-back" of the twist. Also, when changing threads, any difference in coefficient of friction between the threads will give different tensioning effects.

2

Another property that a thread tensioning device must have in certain applications is the ability to prevent the slow passage of thread through the device, called "creep," whenever the thread is stopped. This property is especially desirable in warping or creeling, for if it should be necessary to stop the operation for any reason, such as the rethreading of a broken end, this creep effect would temporarily lower the tension of the ends being warped, giving rise to undesirable effects.

It is therefore an object of this invention to provide an improved tensioning device of simple construction that can supply an additive pinch tension to a thread being passed therethrough.

It is another object of this invention to provide an improved tensioning device of simple construction that will impart an additive tension to a running thread that is not appreciably affected by the velocity of the thread, by the pretension in the thread, or by the coefficient of friction of the thread.

It is a still further object of this invention to provide an improved tensioning device that will permit the passage of twisted thread without any run-back of twist.

It is a still further object of this invention to provide an improved tensioning device that is effective in preventing the creep of thread through the device when the thread has been stopped under tensions.

Other objects and advantages of this invention will become apparent from the following detailed description thereof, when considered in conjunction with the accompanying drawings wherein:

Figure 1 is a side view of one embodiment of the device constructed according to this invention;

Figure 2 is another embodiment of the same device; and

Figure 3 is a vector diagram of the forces acting on one point of the device.

Referring now in greater detail to Figure 1, numeral 10 represents a running thread passing through the device between two aligned thread guides 11 and 12. A plate-shaped non-resilient stationary shoe 13 is rigidly positioned on one side of the thread 10 by any suitable means, not shown, while on the other side of thread 10 is located a non-resilient movable shoe 14, which is similar in shape to stationary shoe 13. Shoe 14 is rotatably connected by means of hinge pin 15 to an arm 16, which is rotatably connected to a stationary axle 17, fastened to the frame of the machine by means not shown. A spiral spring

18 is connected at its central end to axle 17, and at the other end to rotatable arm 16 at point 19 in such a manner that the action of spring 18 urges arm 16 in a downward direction, causing movable shoe 14 to bring pressure against thread 10 as it moves upwardly in frictional contact with stationary shoe 13.

Since arm 16 is mounted for pivotal movement about axle 17 it can be seen that spring 18 biases arm 16 in a clockwise direction as it is viewed in Figure 1.

For effective operation, both movable shoe 14 and stationary shoe 13 should be chamfered or rounded off at the ends in the manner shown in the drawing. For even distribution of pressure by movable shoe 14, it is necessary that hinge pin 15 be located centrally of the shoe.

It will be noted that the arm 16, as shown in Figure 1, lies at an angle to a plane normal to the path of thread travel between the aligned guides 11 and 12. The plane normal to the thread path is designated as A and the angle defined between that plane and the arm 16 is designated as α . The shoe 14 is not shown in its position of maximum proximity to the shoe 13 but is biased toward that position by the spring 18. Thus the shoe 14 is capable of movement both closer to and further from the shoe 13 to vary the pinch applied to the thread. As an important part of this invention the friction between the thread and the shoes is effective to control the relative position of the shoes and the pressure of the pinch applied thereby.

In operation, the functioning of this device is extremely simple. For understanding the action of it, it is necessary to refer briefly to the effect upon the coefficient of friction between a running thread and a tensioning device with various conditions of thread velocity. When a pinch device similar to that described above, but lacking in the movable arm mechanism, is used to tension a thread, it has been found that, with a constant load upon the two tensioning elements, the output tension of the device is far from constant. As the thread speed is increased with a constant pretension, the output tension increases fairly regularly, although not linearly. Since the load upon the tensioning device is constant, the only explanation for this increase in tensioning can be the increase in the coefficient of friction between thread and device. This may be rather difficult to explain in light of the usual concept of coefficient of friction, so that hereafter this coefficient of friction will be interpreted as meaning the degree of frictioning coupling, or effective coefficient of friction between thread and device.

The device of the present invention utilizes changes in the effective coefficient of friction to adjust the loading force exerted upon the two elements of the tensioning device in such a manner that as the coefficient of friction increases, the loading force decreases, thereby giving a "balancing" action.

This balancing action will be more readily understood by referring in greater detail to Figure 3, which represents the forces acting upon a single point of the movable shoe of the device of the present invention as described above.

The point which will be used in this vector analysis will be a point on the surface of movable shoe 14 immediately underneath hinge pin 15, which point will be considered to be a free body. The spring 18 which urges movable shoe 14 both to the right as shown in Figure 1, against the thread and downwardly counter to the direc-

tion of thread travel, has an effect which can be represented by two corresponding vector forces, F_N , tending to move the free body to the right, and F_H , tending to move the free body downwardly. The force F_N , by the basic laws of mechanics must be opposed by an equal and opposite force F_T . The vector F_T , in turn, may be resolved into two equivalent vector forces, F_A , acting along movable arm 16, and F_B acting parallel to the direction of thread travel. As shown in Figure 3, the vector sum of F_A and F_B is numerically equal to F_T .

The drag between the thread surface and the movable shoe surface is dependent upon the effective coefficient of friction and the magnitude of force F_N , according to the following equation:

$$F_F = \mu F_N \quad (1)$$

wherein F_F is the drag force of the movable shoe upon the thread, μ is the effective coefficient of friction, and F_N is the force acting perpendicular to the thread.

It was shown above that movable arm 16 was inclined from a perpendicular drawn from axle 17 to stationary shoe 13 by the small angle α . By the laws of trigonometry, it can be shown that:

$$F_B = \tan \alpha F_T$$

However, since F_T is equal to F_N , then

$$F_B = \tan \alpha F_N \quad (2)$$

Considering now the three forces acting in the direction of thread travel, an equilibrium must exist as follows:

$$F_H = F_F + F_B \quad (3)$$

The equations of F_F and F_B from (1) and (2) respectively can now be substituted in Equation 3, which thus becomes

$$F_H = \mu F_N + \tan \alpha F_N$$

which can then be revised to give

$$F_N = \frac{F_H}{\tan \alpha + \mu} \quad (4)$$

The total tension S , which is imparted to the thread, will obviously be twice the drag exerted by each shoe, or,

$$S = 2F_F \quad (5)$$

but since from Equation 1

$$F_F = \mu F_N$$

$$S = 2\mu F_N$$

Substituting the value of F_N from Equation 4 into 5 then gives the equation

$$S = \frac{2\mu F_H}{\tan \alpha + \mu} \quad (6)$$

Assuming now that $\tan \alpha$ has a small value and that μ is increased, it can be seen that in the above equation, the numerator contains μ , tending to give a tension increase that is proportional to the increase in μ . The denominator, however, consists of the sum of μ and a small constant, so that if μ increases, the denominator also increases, but not in a linear manner. By keeping $\tan \alpha$ small as compared to the value of μ , the increase in the value of the denominator is nearly linear, and therefore, the effect of large increases in μ is to give only a slight rise of output tension S .

This can also be shown in another manner by rearranging Equation 6 to give

$$S = \frac{2F_H}{\tan \alpha + 1} \quad (7)$$

In this instance, by keeping $\tan \alpha$ small, it can be seen that large variations in μ are "dampened," and thus the sum of the constant 1 and the fraction

$$\frac{\tan \alpha}{\mu}$$

is relatively constant.

The embodiment disclosed in Figure 1 depicts the basic principles of this invention. A further modification is shown in Figure 2, in which a positioning ring 20 is fastened about axle 17 to enable adjustment of the spring tension by means of clamp 21, which adjustably connects spring 18 to ring 20. A connecting chain 22 is provided to transmit the action of spring 18 to movable shoe 14 at hinge pin 15. If higher or lower tensions are desired, clamp 21 can be adjusted in either a clockwise or counter-clockwise direction respectively on positioning ring 20. In this manner, the tension of the thread as it leaves the device can be very easily adjusted.

Other means can be used to load arm 16 than the spring 18. For example, a weight can be suspended from the arm, or other types of springs with or without supplementary adjustable weights can be employed.

Further flexibility can be obtained if the distance of the fixed axle 17 from stationary shoe 13, or if the length of rotatable arm 16 is made adjustable. The length of arm 16 should be relatively great in comparison with the thickness of the thread, for in this manner small variations in the thickness of the thread being wound produce relatively small deflections of movable shoe 13, which in turn produce small variations in the angle α . As long as these angular variations remain small, the necessity for adjusting the separation of fixed axle 17 from the stationary shoe 13, or the length of arm 16 is often eliminated.

When an irregularity, such as a fluff, occurs in the running thread, which could give rise to an increased tensioning, the shoe gives way easily. As compared to earlier pinch type tensioning devices, the device of the present invention also possesses the feature that if the thread should be broken between tensioning device and collection package, the device will clamp the thread in position to facilitate subsequent rethreading operations.

By chamfering or rounding off the ends of the two shoes, and by using shoes which are relatively long, the pressure on the thread at any given point can be small, even though the total force between shoes and thread may be high. This low pressure on the thread effectively prevents run-back of twist, even when highly twisted yarns, such as crepe yarns, are wound. If it is desired to gradually increase or decrease the pressure on the thread as it passes through the tensioning device, hinge pin 15 can accordingly be located out of center of shoe 14.

A further advantage resulting from this low pressure on the thread resides in the relatively small amount of wear or "cutting-in" of the running thread on the shoe surfaces. This cutting-in has been a problem in earlier pinch devices, which in some instances have overcome it by

utilizing traversing mechanisms to prevent the thread from following any one continual line of travel through the tensioning device. Such mechanisms are not needed in this invention.

5 In operation, when the angle α is less than 10°, and preferably about 5°, the drag imparted by the two pinching shoes is practically independent of the coefficient of friction between the thread and the shoes. It is desirable to use the 10 same material for both shoes, using polished steel or any other suitable material. When the angle α is about 5°, it has been found that the increase in tension imparted by this device to the thread is practically independent of the speed of the pretension in the thread. Creep-through, when the thread is stopped, is practically eliminated by the use of this device.

15 It is understood that this invention is not intended to be limited to the embodiments given 20 in the foregoing description, but only to the extent of the appended claims.

What is claimed is:

1. A thread tensioning device comprising spaced guides defining a thread path therebetween, a 25 fixed elongated flat rigid tensioning shoe presenting a surface parallel and contiguous to the thread path, a movable elongated flat rigid tensioning shoe presenting a surface contiguous to the thread path, a pivot arm mounting said movable shoe for arcuate movement in a plane parallel to the thread path and perpendicular to the surface of the fixed shoe toward and away from said stationary shoe from a normal position slightly away from the position of maximum 30 proximity of said shoes, said arm being inclined about a stationary axle perpendicular to said plane in such a manner that an angle of between zero and ten degrees is formed between said arm and perpendicular from said axle to said stationary shoe, said movable shoe being closer to the output thread guide than to the input thread 35 guide, and means to bias said movable shoe toward said position of maximum proximity.

2. A thread tensioning device comprising a 45 pair of elongated flat tensioning shoes coacting to pinch therebetween a thread being passed along a path defined by two spaced line guides, one of said shoes being stationary and parallel and contiguous to the surface of said thread path, the other shoe being movable and pivotally 50 connected at its center to an arm, said arm lying in a plane containing the thread path and perpendicular to the surface of said shoes, and being rotatably connected about a stationary axle perpendicular to said plane, and inclined towards the output thread guide so as to form an angle of between zero and ten degrees with a perpendicular from said stationary axle to said stationary shoe, and means for yieldingly urging said movable arm in a direction to cause said movable shoe to tend to move arcuately counter to the direction of the thread and against said stationary shoe.

3. A thread tensioning device comprising a 55 pair of flat tensioning shoes coacting to pinch therebetween a thread being passed along a path defined by two spaced thread guides, one of said shoes being stationary and parallel and contiguous to the surface of said thread path, the other shoe being movable and pivotally connected to an arm, said arm lying in a plane containing the thread path and perpendicular to the surface of said shoes, and being rotatably connected about an axis perpendicular to said plane, and inclined so as to form an angle not greater

than 10° with a perpendicular from said axis to said stationary shoe, and means for yieldingly urging said arm in a direction to cause said movable shoe to tend to move arcuately counter to the direction of the thread and against said stationary shoe.

4. A thread tensioning device comprising spaced guides defining a thread path therebetween, a fixed elongated flat rigid tensioning shoe presenting a surface parallel and contiguous to the thread path, a movable elongated flat rigid tensioning shoe presenting a surface contiguous to the thread path, each of said shoes having bevelled edges at the ends thereof, a pivot arm connected to the center of said movable shoe mounting said movable shoe for arcuate movement in a plane parallel to the thread path and perpendicular to the surface of the fixed shoe toward and away from said stationary shoe.

5
10

from a normal position slightly away from the position of maximum proximity of said shoes, said arm being inclined about a stationary axle perpendicular to said plane in such a manner that an angle of between 0 and 10° is formed between said arm and a perpendicular from said axle to said stationary shoe, said movable shoe being closer to the output thread guide than to the input thread guide, and adjustable means to bias said movable shoe toward said position of maximum proximity.
